UNITED STATES PATENT OFFICE.

ANDREW L. RIKER, OF BRIDGEPORT, CONNECTICUT, ASSIGNOR TO THE "LOCOMOBILE"
COMPANY OF AMERICA, OF NEW YORK, N. Y., A CORPORATION OF WEST VIRGINIA.

INTERNAL-COMBUSTION ENGINE.

1,215,863.

Specification of Letters Patent. Patented Feb. 13, 1917.

Application filed May 16, 1910. Serial No. 561,751.

To all whom it may concern:

Be it known that I, ANDREW L. RIKER, a citizen of the United States, and a resident of Bridgeport, in the county of Fairfield and State of Connecticut, have invented an Improvement in Internal-Combustion Engines (Case E,) of which the following description, in connection with the accompanying drawings, is a specification, like letters 10 on the drawings representing like parts.

This invention relates to internal combustion engines and consists in improvements both in the operation and construction thereof.

15 The invention will be best understood by reference to the following description when taken in connection with the accompanying illustration of one specific embodiment thereof, the scope of the invention being 20 particularly pointed out in the appended claims.

In the drawings.

Figure 1 is a vertical, sectional elevation taken through a cylinder and the crank casting of a multiple cylinder engine embodying 25 one form of the invention;

30 Figs. 2 to 5 inclusive are somewhat diagrammatic views in central vertical section of the positions assumed by the sleeve valves during the suction, the compression, the power and the exhaust stroke of the piston;

Fig. 6 is a view similar to Fig. 1, of a somewhat modified form of the invention;

35 Figs. 7 to 10 inclusive are transverse sections taken through the sleeve or cup valves and showing the different positions assumed thereby during one complete cycle of operations; and

40 Fig. 11 is a vertical section of a still further modified form of my invention.

Referring to the drawings and to that embodiment of my invention herein selected for illustrative purposes, I have there shown 45 the construction of one cylinder of a four cylinder engine. This engine is illustrated as of a size and form suitable for automobile use, but is thus shown for illustrative purposes only, the invention being independent 50 of the form, type or size of the engine employed, and also independent of its utilization in an engine having either a single cylinder or a plurality of cylinders.

55 The engine is shown as supported upon the crank casing 1, in which is suitably

journalled the engine crank shaft 2, having a crank and pin connection 3 to the piston rod 4, which latter has a trunk connection to the cylinder piston 5. The piston is adapted to reciprocate within a suitable and preferably 60 upright cylinder 6, the latter being herein shown as surrounded by the usual water jacket 7, and having its end closed by an appropriately shaped head 8, in which latter is fitted the usual ignition apparatus, not 65 herein shown. The latter may be of any suitable nature, but herein is of the jump spark type, having electrical connections to a suitable high potential source of current.

70 While my invention as to certain of its features is not limited to the type of engine employed, the particular form of engine shown is constructed upon the "Otto" or four cycle principle, and presents features 75 of novelty in its mode of operation, particularly in respect to the introduction of the fuel charged air into the working cylinder of the engine and the discharge of the spent gases therefrom.

70 Designed to coöperate particularly with this type of engine, but also having useful application to engines which are constructionally quite different from the one described, there are provided various features 85 of novelty to be hereinafter more particularly pointed out.

I contemplate the provision of two sleeve valves, one positioned within the other, and both telescoping with the cylinder 6, either 90 interiorly or exteriorly thereof, but preferably interiorly, and controlling the admission of the fuel mixture and the exhaust of the spent gases.

95 In Figs. 1 and 2, wherein I have represented one embodiment of my invention, the admission passage for the fuel mixture is indicated at 9 and the exhaust passage for the spent gases is indicated at 10, these two 100 passages circumscribing the cylinder to the requisite extent, and being preferably oppositely positioned. Within the scope of my invention these passages, or either of them, may be of greater or less peripheral extent.

105 Within the head 8 of the engine, I have positioned a sleeve valve 11 of ring like form and having a sliding engagement with the inner surface of said cylinder which may be of somewhat enlarged diameter above the upper limit of movement of the piston 5, as indicated. The second sleeve 12 is prefer-

ably of substantially the same construction as the valve 11, but is of smaller size and is mounted therein so as to reciprocate upon the inner face thereof. Both of said sleeve valves are partially positioned within the head 8 as indicated in Fig. 1.

The outer sleeve valve 11 has a port or ports 12 adapted to be placed in communication with the inlet passage 9. The opposite wall of said valve 11, being that adjacent the exhaust passage 10, is provided with a port or ports 13, preferably positioned at a higher elevation than the inlet port 12. The inner sleeve valve 14 is provided with a port or ports 15 adapted to be placed in communication with the inlet passage 9 of the cylinder and at its opposite side, being that adjacent the inlet passage 9, it is provided with a port or ports 16 adapted to be placed in communication with the exhaust passage 10. The port 16 is in this embodiment of the invention placed at a higher elevation than the port 15.

Any suitable means may be employed to operate and preferably to reciprocate the said sleeve valves. Herein for the purpose I have shown the sleeve valve 11 as provided with opposite ears 16' tapped to receive bolts or studs 17, the upper ends whereof are received in the ends of the plate 18 to which is jointed a link 19, the upper end whereof is jointed to the arm 20 of a lever pivoted at 21 in a suitable bracket upstanding from the head 8, the opposite arm 22 of said lever being jointed to a vertical rod 23, the lower end whereof is jointed to a crank arm 24 upon a shaft 25. The shaft 25 is preferably driven from the shaft 2, and for that purpose I have herein shown a gear 26 upon said shaft 25 meshing with and driven by a gear 27 upon the shaft 2, said shafts 25 and 2 rotating in the ratio of one to two.

The inner sleeve valve 14 is provided at diametrically opposite points with ears, not shown, into which are tapped bolts or studs 28, one of which is shown in Fig. 1. Said bolts 28 are secured in the ends of a plate 29 positioned transversely to the plate 18, as indicated. To said plate 29 is jointed a link 30, the upper end whereof is jointed to an arm 31 of a lever pivoted at 32 upon a bracket upstanding from the head 8, the opposite arm 33 of said lever being jointed to a rod 34, the lower end whereof is jointed to a crank arm 35 mounted upon a shaft 36. Said shaft 36 is preferably driven from the shaft 2 by the intermeshing gears 37 and 27, in the ratio of one to two.

A complete cycle of operations of that embodiment of my invention shown in Fig. 1 is preferably substantially as follows: At or about the commencement of the suction or charging stroke of the piston 5, the sleeve valves 11 and 14 are in the position shown in Figs. 1 and 2, the crank arm 35 being ad-

vanced substantially 90° with respect to the crank arm 24. The piston 5 is then at the limit of its inward or upward movement, and the admission passage 9 is closed by the outer sleeve valve 11, which as illustrated in Figs. 1 and 2 occupies a lower position than the inner sleeve valve 14. As the piston 5 commences its suction or charging stroke, the inner sleeve valve 14 commences to move downwardly and the outer sleeve valve 11 commences to move upwardly. Therefore, during the suction stroke of the piston the ports 12 and 15 of said valves are sufficiently in register to admit a charge from the passage 9. At the end of the suction stroke, the inner sleeve valve 14 is moved downward sufficiently to cut off the admission of fuel through the inlet admission passage 9, this position of the parts being indicated in Fig. 3. At this time the outer sleeve valve 11 has risen sufficiently to place its port more or less in register with the admission passage 9, but this is immaterial, inasmuch as admission of fuel is prevented by the position of the port 15 in the inner sleeve valve 14. The position of the parts at the end of the compression stroke is indicated in Fig. 4. Although both sleeve valves 11 and 14 have continued to move, their admission ports have not simultaneously been brought into register or partial register with the admission passage 9 during the compression stroke. The position of the parts at the end of the power stroke is indicated in Fig. 5. Although, during the power stroke the sleeve valves 11 and 14 have continued to move, their admission ports 15 and 12 have not simultaneously been brought into register or partial register with the admission passage 9, and hence said passage has remained closed.

During the suction, the compression and the greater part of the power strokes, the exhaust ports 13 and 16 of the sleeve valves have not been brought simultaneously into register or partial register with the exhaust passage 10, and hence said passage has remained closed. At about the termination of the power stroke, as indicated in Fig. 5, however, the said exhaust ports 13 and 16 are brought simultaneously into register with the exhaust passage 10, and therefore during the exhaust or scavenging stroke the spent gases are expelled through the exhaust 10. At the end of said stroke the said sleeve valves 11 and 14 are returned to the position shown in Figs. 1 and 2, thus completing one cycle of operations.

Instead of reciprocating the sleeve valves one within the other, they may be oscillated or rotated. In Figs. 6 to 10 inclusive, I have shown a modified form of my invention wherein the sleeve valves are rotated. In Fig. 6, I have shown a sleeve valve 38 having a closed upper end 39, said valve there-

fore being substantially cup shaped as represented. The head 39 of said valve is provided with a sleeve 40 of reduced diameter and having keyed thereon a beveled gear 41 meshing with a beveled gear 42, fast upon a stud shaft 43 journaled in the bracket 44 rising from the head 8 of the engine. Upon the outer end of the shaft 43 is a spiral or skew gear 45 meshing with a similar gear 46 10 also mounted in said bracket 44 and driven by sprocket or other suitable gearing from the crank shaft 2 of the engine. Positioned within the cup shaped valve 38 is a similarly shaped valve 47 having a closed upper end 15 48 secured to which is a spindle 49 passing through said sleeve 40 and having keyed upon its upper end a beveled gear 50 meshing with the beveled gear 42. The inner valve 47 is provided with an inner port 51 20 and the outer valve 38 is preferably provided with two ports 52 and 53, as clearly indicated in Figs. 7 to 10 inclusive.

The cycle of operations of the form of the engine shown in Figs. 6 to 10 inclusive is 25 substantially the same as that shown in Figs. 1 to 5 inclusive. The valves 38 and 47 are rotated by the beveled gear 42 in opposite directions. At the commencement of the suction or charging stroke the ports 51, 52 30 therein are about to register with each other and with the admission passage 9, as indicated in Fig. 7, and at about the termination of the charging stroke the ports pass wholly out of register and continue out of register 35 until the commencement of another cycle of operations, as indicated in Figs. 8, 9 and 10. Therefore, during the compression and power strokes the admission and exhaust passages remain closed, but during the 40 scavenging or exhaust stroke the second port 51 in the outer sleeve and the port 51 in the inner sleeve are brought wholly or partially into register and into register with the exhaust passage 10, thereby permitting the 45 spent gases to be discharged from the cylinder.

The construction shown in Fig. 11 is substantially the same as that shown in Fig. 1 with the exception of the form and extent of 50 the inner sleeve and the operating means therefor. In said Fig. 11, the outer sleeve 11 preferably remains the same, but for the short, inner sleeve 14 shown in Fig. 1 I have substituted a sleeve 54 preferably extending substantially the entire length of the 55 cylinder and sliding upon the inner face thereof as indicated. The piston 5 reciprocates upon the inner surface of said inner

sleeve 54, the latter being provided with inlet port 55 and exhaust port 56, preferably 60 similar to the corresponding ports 15, 16 shown in Fig. 1. The said sleeve 54 may be operated in the manner described in connection with the said sleeve 14 of Fig. 1, but as herein indicated the lower end of said sleeve 65 54 is connected by a crank arm 57 to the shaft 25. The cycle of operations of that embodiment of my invention shown in Fig. 11 is the same as that embodiment of my invention shown in Fig. 1.

Having thus described one illustrative embodiment of my invention, I desire it to be understood that although specific terms are employed, they are used in a generic and descriptive sense and not for purposes of 75 limitation, the scope of the invention being set forth in the following claims.

Claims:

1. An internal combustion engine comprising in combination, a cylinder having 80 admission and exhaust ports, and a piston reciprocable therein, two concentric sleeve valves within the cylinder slidable upon each other and located beyond the limits of piston travel and each provided with an admission 85 and an exhaust port, a cylinder head extending within the inner sleeve valve, and means differentially to operate said valves.

2. A four cycle internal combustion engine comprising in combination a cylinder 90 having admission and exhaust ports, a piston reciprocable therein, two arc-shaped slide valves positioned within the cylinder beyond the limits of piston travel and one 95 within the other and both ported to control the admission and the exhaust, and means to operate said valves to open the admission port during an outward stroke of the piston and to open the exhaust port during an inward stroke of the piston of the same cycle. 100

3. An internal combustion engine comprising a cylinder, a cylinder head, said cylinder having admission and exhaust ports, independently movable arc-shaped valve plates working between the walls 105 of the cylinder and the cylinder head and beyond the rearward limits of piston travel, and means for moving said valve plates.

In testimony whereof, I have signed my name to this specification, in the presence of 110 two subscribing witnesses.

ANDREW L. RIKER.
